Primary Examiner — Brian N Vinson(74) *Attorney, Agent, or Firm* — Laurence P. Colton; Smith Risley Tempel Santos LLC(57) **CLAIM**

The ornamental design for a toothbrush holder, as shown and described.

DESCRIPTION

FIG. 1 is a top, front, and right side perspective view of a toothbrush holder showing a first embodiment of my new design.

FIG. 2 is a top plan view thereof.

FIG. 3 is a front elevational view thereof, the sides opposite and adjacent being identical in appearance.

FIG. 4 is a bottom plan view thereof.

FIG. 5 is a top, front, and right side perspective view of a second embodiment thereof.

FIG. 6 is a top plan view thereof.

FIG. 7 is a front elevational view thereof, the sides opposite and adjacent being identical in appearance.

FIG. 8 is a bottom plan view thereof.

FIG. 9 is a top, front, and right side perspective view of a third embodiment thereof.

FIG. 10 is a top plan view thereof.

FIG. 11 is a front elevational view thereof, the sides opposite and adjacent being identical in appearance; and,

FIG. 12 is a bottom plan view thereof.
